FOOD TRAY

BACKGROUND OF THE INVENTION

Food trays for holding and heating a food product are well known. One type in common use has a single compartment. When a pasta or other low value product is heated for consumption in the single compartment, any sauce, which may contain meat and or vegetables, is layered on top or beside of the low value product. Heating of the food arranged in this manner causes the flavours to blend and textures to deteriorate. Another food tray has two compartments, one beside the other. Heating does not cause blending of flavour, but having to spoon sauce from one compartment to another for consumption by the customer is inconvenient.

In another food tray available in Europe from InterFrost GmbH, a smaller paperboard tray is nested snugly within a larger paperboard tray. The two trays fit tightly together. Sauce may be placed in the smaller tray, and pasta or rice in the larger tray. Upon heating of the InterFrost food tray, steam may build up in the lower tray, and may be released suddenly when the smaller tray is removed from the larger tray. In addition, due to the close tight fit of the smaller tray in the larger tray, the smaller tray tends to stick in the larger tray, and pulling on the smaller tray can result in a sudden release of the smaller tray, causing a risk of spilling hot food product from the smaller tray. The steam and heat generated from the lower tray may cause the upper tray to deconstruct, which increases the probability of spillage. Risk of steam release and hot food spill makes the food tray somewhat of a hazard to use.

SUMMARY OF THE INVENTION

The food tray of the present invention is intended to provide the advantages of separate heating of low and high value food products, while reducing the risk of spillage and steam release. In addition, the food tray of the present invention is convenient to use, and provides a pleasing aspect to the user.

Therefore, according to an aspect of the invention, there is provided a food tray, comprising a lower tray containing a first food product and an upper tray nested stably at least partly inside the lower tray, with the upper tray containing a second food product. An air permeable interface is provided between the upper tray and lower tray to allow venting of steam from the lower tray during cooking. A cover is provided for the upper food tray. Each of the lower tray and the upper tray are preferably formed of a material that is suitable for use in a microwave oven. Various constructions may be used to create the air permeable interface, such as lugs, ledges and lips. The upper tray may sit above the lower tray. The trays are preferably nested loosely for ease of removal of the upper tray from the lower tray. Various configurations of cover may be used such as a sleeve, carton, lid or plastic film. The upper tray may contain the higher value food product.

According to a further aspect of the invention, there is provided a method of cooking food products of different value, the method comprising the steps of providing a food tray comprising a first food product in a lower tray and a second food product in an upper tray nested loosely in the lower tray; and subjecting the food tray to food heating energy while permitting steam to escape from the lower tray.

These and other aspects of the invention are set out in the claims, which are incorporated here by reference.

BRIEF DESCRIPTION OF THE FIGURES

Preferred embodiments of the invention will now be described with reference to the figures, in which like reference characters denote like elements, by way of example, and in which:

2

FIG. 1 is a section through a food tray comprising an upper tray and lower tray according to an embodiment of the invention;

FIG. 2 is a top view of the food tray of FIG. 1;

FIG. 3 shows the food tray of FIG. 1 with a cover;

FIG. 4 shows an embodiment of the invention with a snap-on cover;

FIG. 5 is a section through a further embodiment of a food tray according to the invention;

FIG. 6 is a section through a still further embodiment of a food tray according to the invention; and

FIG. 7 is a top view of the upper food tray shown in FIG. 6.

DETAILED DESCRIPTION OF PREFERRED EMBODIMENTS

In the claims, the word "comprising" is used in its inclusive sense and does not exclude other elements being present. The indefinite article "a" before a claim feature does not exclude more than one of the feature being present.

As shown in FIGS. 1 and 2, a food tray is formed from a lower tray 10 and an upper tray 12 nested stably at least partly inside the lower tray 10. An air permeable interface 14 is provided between the upper tray 12 and lower tray 10 by outwardly extending lugs 16 at the corners of the upper tray 12. The lugs 16 rest on top of the upper edge 18 of the lower tray 10 with a gap 19 between the upper tray 12 and lower tray 10. The gap 19 may extend around the perimeter of the lower tray 12. With a gap between the lower tray 10 and upper tray 12, when product in the lower tray 10 is heated, any steam produced can vent through the gap 19.

The lugs 16 and gap 19 permit the upper tray 12 to sit loosely on the lower tray 10. The only force retarding removal of the upper tray 12 from the lower tray 10 is the force of gravity on the upper tray 12 and its contents. Removal of the upper tray 12 from the lower tray 10 is therefore frictionless. The lugs 16 are at the corners of the upper tray 12 as shown, but may be anywhere around the periphery of the upper tray 12. Four lugs are convenient, and there should be a sufficient number of lugs suitably spaced around the periphery of the upper tray 12 so that the upper tray is stable, and is resistant against tipping. To assist stability, the lugs 16 should be near the top of the upper tray 12 so that the main mass of the upper tray 12 and its contents are below the lugs 16.

Both the upper tray 12 and lower tray 10 include respective lips 32 and 30. The lips 32, 30 should be at least 3 mm wide for easy of sealing.

Each of the lower tray 10 and upper tray 12 may be made by injection moulding, thermoforming or any other suitable manufacturing process. The sidewalls 20 of the lower tray 10 and the sidewalls 22 of the upper tray 12 each may have the same nesting angle. The nesting angle of a tray is the angle between the sidewalls and a perpendicular to the plane defined by the upper edge of the tray. The upper tray 12 may be made in the same mould as the lower tray 10, but with an insert in the mould to reduce the volume. The upper tray 12 and the lower tray 10 should be formed of a material that is suitable for use in a microwave oven, and also may be formed of a material suitable for use in a conventional oven. Exemplary materials are paper, polypropylene (microwave only) and dual use CPET (crystalline polyethylene terephthalate) available from a number of manufacturers. CPET is particularly suitable due to its wide temperature tolerance. The trays 10, 12 may be transparent or opaque.

As shown in FIG. 3, the food tray is preferably provided with a cover 24, such as a sleeve. The sleeve may be a paperboard sleeve into which the combined trays 10 and 12, are

inserted. The cover 24 could also be a carton that encloses both trays 10 and 12 completely.

As shown in FIG. 4, the cover may comprise a snap-on microwavable lid 26 for the upper tray 12. The lid 26 may extend over the lip 20 on the lower tray 10. The cover 24 may also include a film that is heat sealed to the lip 32 on the upper tray 12. The film may be on the underside of a cardboard sleeve, or a stand alone cover heat sealed to the lip 32.

As shown in FIG. 4, the air permeable interface may be formed by a seat created by lugs or ledges 28 formed in the sidewalls 20 of the lower tray 10 and spaced around the periphery of the lower tray 10, with the upper tray 12 resting directly on the lugs or ledges 28. Preferably, the lugs or ledges 28 are discontinuous or provided with openings to allow the escape of steam during cooking. As shown in FIG. 6, the air permeable interface may be formed by the lip 32 resting directly on the upper edge 18 of the lower tray 10. In this case, as shown in FIG. 7, the lip 32 is preferably provided with protrusions 34 for allowing steam release. In each of these cases, it is preferable that the air permeable interface supports the upper tray 12 in the lower tray 10 so that the lip 32 of the upper tray 12 sits above the lower tray 10. In the example of FIG. 7, the outwardly extending lip 32 of the upper tray 12 sits loosely on the upper edge 18 of the lower tray 10 to form the air permeable interface with a gap 29 between the side walls 22 of the upper tray 12 and the sidewalls 20 of the lower tray 10. The upper tray 12 and lower tray 10 may also have fluted sides to allow venting of steam during cooking. In another embodiment, the upper tray 12 may sit entirely within the lower tray 10 on lugs or ledges, with a handle provided on the upper tray 12 to allow the upper tray 12 to be easily removed from the lower tray 10.

Food is placed in each of the upper tray 12 and lower tray 10. The food product 42 in the upper tray 12 may be a higher value food product in terms of cost per weight than the food product 40 in the lower tray 10. Thus the lower tray 10 may include pasta, rice or vegetable, which is usually the higher volume product. The upper tray 12 may include a sauce, such as cheese sauce, meat or seafood sauce, or vegetable sauce. Water may be added to the lower tray 10 to assist in cooking the food product in the lower tray 10. Preferably, a gap 44 is provided between the top of the food product 40 and the bottom 46 of the upper food tray 12 to avoid the food product 40 coming into contact with the bottom 46 of the upper food tray 12. In another embodiment, chili may be placed in the lower tray 10 and a biscuit in the upper tray 12. For food product such as a biscuit that should have a crisp exterior texture when cooked, a susceptor board may be placed in the tray with the food product.

When sold, the food tray, including food, may be wrapped in shrink wrap. For use, the customer removes the shrink wrap and deposits the food tray in an oven (conventional or microwave as appropriate for the materials), where the food tray is subject to food heating energy. If the upper tray 12 is sealed with a film, it may be removed or loosened prior to cooking depending on the cooking instructions. Due to the air permeable interface 14, the food tray permits steam to escape from the lower tray. Upon removal of the food tray from the oven, the higher value food product may be added to the lower value food product, simply by pouring the higher value food product into the lower tray. Due to the product being in separate trays, quicker more even heating is obtained. With the higher value product in the top tray, the aromas of the higher value product are easily available to the customer upon heating, and the higher value product also presents a pleasing aspect to the customer.

Either or both the cover 24 or the sidewalls 20, 22 may be provided with graphics illustrating the food product and providing instructions for use. In addition, there may be a stack of upper trays, all nested one above the other in like manner as upper tray 12 is nested in lower tray 10. The additional upper trays may conveniently have the same structure as the upper tray 12, and may contain different food products from those in upper tray 12, lower tray 10 or the other upper trays.

Immaterial modifications may be made to the embodiments of the invention described here without departing from the invention.

What is claimed is:

1. A food tray, comprising

a lower tray containing a first food product, the lower tray having a base, a rim and sidewalls, the sidewalls extending vertically from the base to the rim, the sidewalls having a discontinuous ledge formed therein, the discontinuous ledge positioned entirely between the base and the rim of the lower tray and projecting inwardly to the lower tray;

an upper tray containing a second food product, the upper tray having a base, wherein the base of the upper tray rests on the discontinuous ledge so that the upper tray is nested at least partly inside the lower tray above the first food product and so that a gap is formed between sidewalls of the upper tray and sidewalls of the lower tray, wherein an air permeable interface is formed between the upper tray and the lower tray at points of discontinuity of the ledge;

a cover for at least one of the lower tray or the upper tray; and

at least one of the lower tray or the upper tray being formed of a material that is at least partially microwave transparent for cooking of the first food product in the lower tray and the second food product in the upper tray, wherein the air permeable interface and the gap are configured to permit steam to escape from the lower tray during cooking of the first food product.

2. The food tray of claim 1 in which the cover comprises a cardboard sleeve that fits over both the upper tray and lower tray.

3. The food tray of claim 1 in which the cover comprises a snap-on microwavable lid for the upper tray.

4. The food tray of claim 1 in which the cover extends around a lip on the lower tray.

5. The food tray of claim 1 in which the upper tray and lower tray are each made of transparent material.

6. The food tray of claim 1 in which the upper tray is nested in the lower tray such that gravity retards removal of the upper tray from the lower tray.

7. The food tray of claim 1 in which the first food product is a lower value product than the second food product.

8. The food tray of claim 7 in which the first food product comprises pasta or rice.

9. The food tray of claim 1 in which the second food product comprises meat or seafood.

10. The food tray of claim 9 in which the second food product comprises a sauce.

11. The food tray of claim 1 in which the food tray is wrapped in shrink wrap.

12. A food tray, comprising

a lower tray containing a first food product, the lower tray having a base, a rim and a sidewall, the sidewall extending vertically from the base to the rim to define a volume, the sidewall having a discontinuous ledge formed entirely between the base and rim, the discontinuous ledge projecting inwardly to the lower tray;

5

an upper tray having a base, wherein the base of the upper tray rests on the discontinuous ledge of the lower tray such that at least part of the upper tray is inside the lower tray above the first food product, the upper tray containing a second food product, wherein an air permeable interface between the lower tray and the upper tray is formed at points of discontinuity of the ledge to permit steam to escape from the lower tray during cooking of the first food product;

at least one of the lower tray or the upper tray being formed of a material that is at least partially microwave transparent for cooking of the first food product in the lower tray and the second food product in the upper tray; and a cover for at least one of the lower tray or the upper tray.

13. A food tray comprising:

a lower tray containing a first food product, the lower tray having a base, a lip forming a rim and a sidewall, the sidewall extending vertically from the base to the rim to define a volume, the sidewall having a discontinuous ledge formed entirely between the base and rim, the discontinuous ledge projecting inwardly to the lower tray;

an upper tray, the upper tray having a base, a lip forming a rim and a sidewall, the sidewall of the upper tray extending vertically from the base of the upper tray to the rim

5

10

15

20

6

of the upper tray to define a volume, wherein the base of the upper tray rests on the discontinuous ledge of the lower tray such that at least part of the upper tray is inside the lower tray above the first food product, the upper tray containing a second food product, wherein an air permeable interface between the lower tray and the upper tray is formed at points of discontinuity of the ledge to permit steam to escape from the lower tray during cooking of the first food product;

at least one of the lower tray or the upper tray being formed of a material that is at least partially microwave transparent for cooking of the first food product in the lower tray and the second food product in the upper tray; and a cover for at least one of the lower tray or the upper tray, wherein the lip of the upper tray is spaced apart from and located above the lip of the lower tray to permit steam to pass between the lips.

14. The food tray of claim 1, wherein the discontinuous ledge is positioned between the base and the rim of the lower tray and projects inwardly beyond an intersection point between the sidewall of the lower tray and the base of the lower tray where the sidewall of the lower tray extends from the base of the lower tray to the rim of the lower tray.
